METHOD OF MAKING YOKES FOR GARMENT HANGERS

Filed Aug. 24, 1946

UNITED STATES PATENT OFFICE

2,460,939

METHOD OF MAKING YOKES FOR
GARMENT HANGERSWalter Ludwig, Detroit, Mich., assignor to L. A.
Young Spring & Wire Corporation, Detroit,
Mich.

Application August 24, 1946, Serial No. 692,766

9 Claims. (Cl. 93—1)

1

This invention relates to improvements in method of making a yoke for a garment hanger.

The main objects of the invention are:

First, to provide a yoke for a garment hanger and a method of producing the same, which yoke is of tubular cross section and of fibrous material and which is conformed and shaped to provide strength and rigidity and adapted to smoothly engage a garment supported thereon.

Second, to provide a garment supporting member and a method of producing the same, which supporting member is of tubular cross section and of fibrous material and in which the bottom wall thereof is conformed and shaped to facilitate the ready connection thereto of garment supporting means to dependably support a garment from beneath said supporting member.

Third, to provide a garment supporting member of the type above described and a method of making the same which facilitates economy of production.

Further objects relating to details and economies of construction and method of production will appear from the description to follow. The invention is defined in the claims.

Structures and steps in the method of production, illustrating preferred embodiments of the invention are shown in the accompanying drawing in which:

Fig. 1 is a plan view of a paper tube to be conformed and shaped to provide the yoke of the garment hanger.

Fig. 1A is an enlarged fragmentary perspective view of the end of the paper tube of Fig. 1, illustrating a step in the method of producing the same.

Fig. 2 is a central longitudinal vertical section of the tubular yoke and die members illustrating a step in the method of conforming the yoke to shape.

Fig. 3 is an enlarged view in vertical section taken on the line 3—3 of Fig. 2.

Fig. 4 is an enlarged view in vertical section on the line 4—4 of Fig. 2 illustrating a step in the method of conforming the apex of the yoke to shape.

Fig. 5 is an enlarged view in vertical section taken transversely of a yoke arm and transversely of the conforming dies and slit cutting members, illustrating a step in conforming the bottom wall of the yoke arm to form an opening therethrough for receiving means for connecting a garment to the yoke arm.

Fig. 6 is a bottom plan view of the yoke after the steps for conforming the same to shape have been completed, and

2

Fig. 7 is a view in side elevation of the yoke after the steps for conforming and shaping the same have been completed.

Referring to the embodiment of the invention illustrated in the drawing, my garment hanger comprises a yoke 1 having downwardly diverging garment supporting arms 2, this yoke in the preferred embodiment of the invention being of tubular cross section and of fibrous material.

10 The yoke 1 at the apex 4 thereof has its under wall 5 upwardly collapsed against the upper wall 6 of the yoke longitudinally centrally thereof, to provide a longitudinal groove-like recess 7 in the underwall as shown in Figs. 2, 4 and 6 to impart rigidity and strength to the yoke at the apex thereof. The yoke arms 2 are downwardly bent at their outer ends 8 to smoothly engage the garment at the shoulders thereof. These downwardly bent portions are formed by collapsing the under wall of the yoke longitudinally centrally thereof vertically upwardly into abutting relation with the upper wall of the yoke forming the downwardly opening 15 groove-like recesses 9 in the bottom wall as shown in Figs. 2 and 5. These groove-like recesses facilitate bending the end portions 8 into downwardly curved form and impart strength and rigidity to the outer ends of the yoke arms.

20 The method and means as hereinafter described by collapsing the under wall of the yoke longitudinally centrally thereof vertically upwardly into abutting relation with the upper wall of the yoke forming the downwardly opening 25 groove-like recesses 9 in the bottom wall as shown in Figs. 2 and 5. These groove-like recesses facilitate bending the end portions 8 into downwardly curved form and impart strength and rigidity to the outer ends of the yoke arms.

20 The yoke 1 is formed of the paper tube 10 shown in Fig. 1 and conformed to shape between the relatively vertically movable upper and lower conforming die members 11 and 12, conventionally shown in Figs. 2, 3 and 4. The die members are opened into vertically spaced relation to permit the tube 10 to be placed into the conforming cavity of the lower die member 12 after which the die members are closed upon each other, conforming the yoke to the shape 30 shown in Fig. 2. The lower die is provided with an upwardly projecting and longitudinally extending rib-like member 13 at the apex of its conforming cavity, to collapse the lower wall 5 of the yoke against the upper wall 6 and to provide the downwardly opening longitudinally extending recess 7, in the lower wall 5 as shown in Figs. 2 and 4. The lower die member 12 is also provided with upwardly projecting and longitudinally extending rib-like members 14 at the outer ends thereof, to collapse the lower wall of the yoke against the upper wall and to provide the downwardly opening longitudinally extending recesses 9 in the bottom wall of the yoke as shown in Fig. 2. The conforming cavity 15 of the upper die member 11 is downwardly curved at

its outer ends 16 to form the downwardly curved shoulder portions 8 of the yoke.

The yoke arms 2 intermediate the apex 4 of the yoke and the outer ends 8 of the arms are provided with the openings 161 extending transversely through the lower portions of the arms. These openings are formed by cutting spaced longitudinal slits 17 in the underwall of the yoke arms, and collapsing the underwall upwardly on the outer sides 18 of the slits forming the longitudinally extending supporting strands 19 spaced from the upwardly collapsed portions 18 of the bottom wall of the yoke arms, as shown in Figs. 5 and 7. The openings 161 are adapted to receive safety pins or other suitable attaching means for detachably and dependably supporting a garment from beneath the yoke, the loops or strands 19 constituting means for supporting such safety pins or other attaching means.

Referring to Fig. 5 for the method and means of forming the pin receiving yoke openings 161, the pair of slits 17 are cut into the bottom wall of each yoke arm by means of a pair of slit cutting members 28 supportingly mounted within the lower die member 12. These slit cutting members may be fixedly secured to the lower die member or mounted for vertical movement independently thereof. After the cutting edges of the slit cutting members has cut through the lower wall, a further relative inward movement of the cutting members collapses the bottom wall portions 18 upwardly, on the outer sides of the slits. Upon withdrawal of the cutting members by relative movement of cutting members and yoke, the bottom wall portions 18 on the opposite sides of the slits remain permanently upwardly collapsed as shown in Figs. 5 and 7. The slit cutting and forming operation of Fig. 5 may be simultaneously with or before or after conforming operation of Fig. 2. The collapsing of the bottom wall upwardly on the outer sides of the slits 17 is facilitated by the outer beveled portions 21 of the slit cutting members 28.

The paper tube 10 of the yoke is formed of a plurality of plies or layers convolutely or otherwise wound to tubular formation and cemented together. Fig. 1A illustrates a ply 22 of paper having adhesive 23 applied to a surface thereof and being wound to tubular formation. The yoke in its entirety including all the conforming and shaping operations of Figs. 2 and 5 may be performed quite promptly after the tube has been wound to tubular formation and before the glue or adhesive 23 used in cementing the plies or layers together has set. This facilitates slipping of the plies relative to each other during the conforming and collapsing operations, and permanent retention of the same to the conformed or collapsed shape after the adhesive has set.

The foregoing structures are characterized by inexpensiveness in the production thereof, the rigidity and strength thereof, and by effectiveness in smoothly supporting a garment from the top surface of the yoke and dependably supporting a garment from beneath the yoke. The method of producing the same may be readily effected by a relatively few easily performed steps.

The yoke structure previously described constitutes the subject matter of a divisional application.

Embodiments of the invention as to structure and method of producing the same, which incorporate the principles of the invention has

been illustrated and described. It should be understood that the foregoing terminology is used descriptively rather than in limiting sense and with full intent to use equivalents of the features shown and described within the scope of the following claims.

Having thus described my invention, what I claim as new and desire to secure by Letters Patent, is:

10. 1. The method of conforming the garment supporting arms of a yoke member of tubular cross section and of fibrous material, comprising the steps of cutting a pair of parallel slits through and longitudinally of the bottom wall of each yoke arm and upwardly collapsing the bottom wall on the outer sides of the pair of slits to form an opening through the yoke arm for receiving means for dependably supporting a garment from beneath the yoke member.
20. 2. The method of conforming the garment supporting arms of a yoke member of tubular cross section and of fibrous material, comprising the steps of cutting a pair of slits in side by side relation through and longitudinally of the bottom wall of each yoke arm and upwardly collapsing the bottom wall on the outer sides of the pair of slits to form an opening through the yoke arm for receiving means for dependably supporting a garment from beneath the yoke member.
30. 3. The method of conforming the garment supporting arms of a yoke member of tubular cross section and of fibrous material, comprising the steps of cutting a pair of parallel slits through the bottom wall of each yoke arm and upwardly collapsing the bottom wall on the outer sides of the pair of slits to form an opening through the yoke arm for receiving means for dependably supporting a garment from beneath the yoke member.
40. 4. The method of conforming the garment supporting arms of a yoke member of tubular cross section and of fibrous material, comprising the steps of cutting a pair of slits in side by side relation through the bottom wall of each yoke arm and upwardly collapsing the bottom wall on the outer sides of the pair of slits to form an opening through the yoke arm for receiving means for dependably supporting a garment from beneath the yoke member.
50. 5. The method of conforming a garment supporting member of tubular cross section and of fibrous material, comprising the steps of cutting a pair of slits in side by side relation through the tubular wall of said supporting member and collapsing the tube inwardly on the outer sides of the pair of slits to form an opening through the supporting member for receiving means to dependably support a garment from the supporting member, said pair of slits being cut by a pair of cutting members beveled on the outer sides thereof to facilitate said inward collapsing of the wall on the outer sides of the pair of slits.
60. 6. The method of conforming a garment supporting member of tubular cross section and of fibrous material, comprising the steps of cutting a pair of slits in side by side relation through the tubular wall of said supporting member and collapsing the tube inwardly on the outer sides of the pair of slits to form an opening through the supporting member for receiving means to dependably support a garment from the supporting member.
70. 7. The method of conforming a garment supporting member of tubular cross section and of fibrous material, comprising the steps of cutting a pair of slits in side by side relation through the tubular wall of said supporting member and collapsing the tube inwardly on the outer sides of the pair of slits to form an opening through the supporting member for receiving means to dependably support a garment from the supporting member.
75. 7. The method of conforming a garment supporting member of tubular cross section and of

fibrous material comprising the steps of cutting a pair of slits in side by side relation through the tubular wall of the supporting member and collapsing the wall inwardly on the outer sides of the pair of slits to form an opening through said member, said pair of slits being cut by a pair of cutting members having cutting edges and portions offset laterally outwardly from said edges to facilitate said inward collapsing of the supporting member wall on the outer sides of the pair of slits.

8. The method of forming a yoke member for a garment hanger comprising the steps of applying an adhesive to one of the surfaces of a layer of fibrous material, winding said layer to provide a multiply tubular member, conforming said tubular member between conforming die members to provide downwardly diverging garment supporting arms having downwardly curved garment supporting portions at the outer ends of said arms and to provide in the bottom wall beneath said downwardly curved end portions upwardly collapsed portions having downwardly opening longitudinal groove-like recesses and to provide in the bottom wall intermediate the downwardly diverging arms an upwardly collapsed portion having a downwardly opening longitudinal groove-like recess, and slitting and conforming with pairs of slit cutting and conforming members the bottom wall between the intermediate collapsed portion and the collapsed end portions to provide a pair of slits in the bottom wall of each yoke arm with the bottom wall on the outer sides of each pair of slits upwardly collapsed, said die conforming and slit cutting and conforming operations being simultaneously performed before the adhesive between the plies in the tube forming operation has set.

9. The method of forming a yoke member for a garment hanger comprising the steps of applying an adhesive to one of the surfaces of a layer of fibrous material, winding said layer to provide a multiply tubular member, conforming said tubular member between conforming die members to provide downwardly diverging garment supporting arms having downwardly curved garment supporting portions at the outer ends of said arms and to provide in the bottom wall beneath said downwardly curved end portions upwardly collapsed portions having downwardly opening longitudinal groove-like recesses and to provide in the bottom wall intermediate the downwardly diverging arms an upwardly collapsed portion having a downwardly opening longitudinal groove-like recess, and slitting and conforming with pairs of slit cutting and conforming members the bottom wall between the intermediate collapsed portion and the collapsed end portions to provide a pair of slits in the bottom wall of each yoke arm with the bottom wall on the outer sides of each pair of slits upwardly collapsed, said die conforming and slit cutting and conforming operations being performed before the adhesive between the plies in the tube forming operation has set.
